TOY

Louis Marx, New York, N. Y.

Application March 7, 1935, Serial No. 9,708

17 Claims.

(Cl. 46—132)

This invention relates to toys, and more particularly to a climbing toy fireman, especially one combined with water hose and pump mechanism.

The primary object of my invention is to generally improve toys of the climbing fireman type. A more particular object is to combine with such a toy an additional figure toy, for example, a simulated infant, which may be positioned on the ladder at an intermediate point and so related 10 to the fireman during movement along the ladder that the fireman will carry the infant with him.

A further object of my invention is to enhance the realism and play value of the toy by providing the fireman with a water hose connected to a 15 water supply source. In accordance with still another object and feature of my invention, the water supply source is made in the form of a fire hydrant, and a part of the hydrant is manipulable to pump water from the hydrant 20 through the hose.

To the accomplishment of the foregoing and other more detailed objects which will hereinafter appear, my invention consists in the toy elements and their relation one to the other, as 25 hereinafter are more particularly described in the specification and sought to be defined in the claims. The specification is accompanied by drawings in which:

Fig. 1 is a perspective view of a toy embodying 30 features of my invention;

Fig. 2 is a vertical section through the water supply source, and is taken in the plane of the line 2—2 of Fig. 1;

Fig. 3 is an enlarged partially sectioned elevation showing the construction of the toy fireman; and

Fig. 4 is a horizontal section taken in the plane of the line 4—4 of Fig. 3.

Referring to the drawings and more particularly to Fig. 1, the toy comprises a ladder L, a fireman F movable along the ladder, a figure toy preferably in the form of a child C, a water hose H carried by the fireman, and a water supply source S preferably externally simulating a fire hydrant.

Considering the arrangement in greater detail, the ladder L is made of sheet metal pressed to form poles 12 connected by rungs 14. As is best shown in Fig. 4, the poles 12 are tubular in construction, thereby imparting sufficient rigidity to the same and presenting a smooth exterior along which the fireman F is readily slideable. The ladder may, if desired, be made in sections, in which case the ends of one section are dimensioned to be snugly received within the ends of the adja-

cent section, so that the ladder when assembled is effectively continuous. The lower end of the ladder is mounted on a base 16 by means of a pin 18 extending through the ladder and held in ears 20 struck upwardly from the base. The ladder is supported in elevated position by arms 22 preferably forming the ends of a single U-shaped piece of wire the cross bar 24 of which is pivotally mounted on base 16 by bearing lugs 26 rolled upwardly from the base. The ends of arms 22 are 10 turned inwardly and fit into a pair of holes 28 punched through the poles of the ladder. Only one of the holes 28 is visible in Fig. 1. Additional pairs of holes 30 and 32 may be provided along the poles of the ladder, and it will be evident that 15 the angle of the ladder may be changed by spreading the arms 22 apart and permitting them to enter another of the pairs of holes. It will also be understood that the ladder and support arms 20 may be folded down flat on the base for packing or shipment.

The fireman F is best shown in Fig. 3 and comprises a body 34 carrying arms 36 which extend forwardly to the ladder L. The fireman is also provided with legs 38 pivotally and reciprocably 25 mounted on the body by means of a fulcrum spindle 40 passing through vertical slots 42 in the legs. The upper ends of the legs are projected within the body to form extensions 44 respectively connected to rotatable cranks 46 and 48. Cranks 46 30 and 48 may be formed of a single piece of wire and are oppositely disposed in order to move the legs in alternation. The cranks are rotated by an appropriate motor, and in the present case the body of the fireman is provided with a spring 35 motor 50 the main spring of which is wound by a key 52 and which drives a gear 54 meshing with a pinion 56 mounted on the crank shaft. It will be understood that the spring motor and leg extensions are housed within the body of the fireman so that only the lower parts of the legs are 40 visible.

The operating speed of the motor may, if desired, be limited by appropriate governor mechanism. In the present case I employ a simple 45 train of step-up gearing terminating in an eccentric 58 which is rotated at very high speed, thereby tending to limit the motor speed. This eccentric may also be used as part of appropriate control or stop mechanism for the motor, here 50 exemplified by a lever 60 pivoted at 62 and having a brake portion 64 dimensioned to be moved in the path of rotation of eccentric 58, thus positively arresting rotation of the motor. When lever 60 is moved in slot 66 to its opposite posi- 55

tion, the brake 64 is moved out of the path of eccentric 58.

The lower ends of legs 38 are provided with feet 68, and these are dimensioned to fit freely between the successive rungs 14 of the ladder. The throw of cranks 46 and 48 is so dimensioned that while one foot rests on one rung of the ladder, the other foot is moved over the next higher rung of the ladder. In this manner the fireman 10 ascends the ladder.

To stop the fireman at the top of the ladder, I provide stops 70. These stops are preferably made as indentations or notches because it is then readily possible to apply the fireman to the ladder over the upper or free end of the ladder. The arms 36 of the fireman terminate in hands 72 connected by a cross bar 74 (Fig. 4). Lugs 76 are turned inwardly to encompass the poles of the ladder. The upper edges of cross bar 74 are 20 tapered toward the poles of the ladder at 78, and the arrangement and balance of the toy is such that when cross bar 74 nears the top of the ladder, the edges 78 enter notches 70 and arrest continued movement.

25 The figure toy C may take any of a variety of forms and is here illustrated as an infant or child. It is provided with means adapting it to be mounted on the ladder at an intermediate point, and in the present case a simple hook 80 (Fig. 3) is secured to the back of the toy and is dimensioned to fit over any one of the ladder rungs 14. The hook 80 is widely open and is so shaped that the toy is readily moved upwardly off the rung and along the ladder. The child 30 and the fireman are provided with parts so engageable that the fireman will carry the child upwardly with him while ascending the ladder. In the present case I provide a rod 82 extending between arms 36 at such location as to come 40 in back of the legs 84 as of the child and to bear beneath the thighs. In operation, the fireman approaches the child, as shown in solid lines in Fig. 1 of the drawings, and thereupon carries the child upwardly to the top of the ladder, as is 45 indicated in broken lines.

The water hose H is preferably a slender flexible rubber pipe or hose the upper or discharge end of which is provided with an appropriate nozzle 90, and the lower or inlet end 92 of which 50 is connected to the water supply source S. The nozzle end is carried by the fireman, and for this purpose I provide a bent wire support 94 the rear end 96 of which is secured to the cross arm 74 of the fireman, and the forward end of which is 55 bent to form an upright U-portion 98 and an inverted U-portion 100. The hose is supported in U-portions 98 and 100, and is readily applied to or removed from the holder. At the same time the holder directs the hose and nozzle away 60 from the ladder so that the stream of water will be directed toward the building against which the ladder is supposed to be leaning.

Water supply source S comprises a water-proof container 102 which is preferably generally cylindrical in form and which may be detachably received in base 16 by placing the same in a mating opening in the base, as is best shown in Fig. 2. A bead 104 may be rolled outwardly on the wall of container 102 to limit the insertion 70 of the container in the base.

The water supply source preferably simulates a water hydrant, and the lower part of the simulated hydrant is used to carry a supply of water 75 106, while the upper part of the simulated hydrant carries a water pump P for pumping water

upwardly through hose H. In the present case the pump P comprises a flexible rubber ball 108 supported in the upper part of the casing by a pedestal 110. Ball 108 is provided with valve nipples 112 and 114, the valve in nipple 112 being arranged for intake, and the valve in nipple 114 being arranged for discharge. A short length of pipe 116 is secured to nipple 112 and communicates with the body of water 106. The end 92 of hose H passes through a projection 118 10 on the side wall of the hydrant and is connected to discharge nipple 114.

The pump is operated by a depressible button 120 which is reciprocably received in the top 122 of the casing. The button is normally held in 15 upward position by the ball 108, and its upward movement is limited by a flange 124. The manner in which the jump is operated by means of the button is self-evident from inspection of Fig. 2. It may be observed that button 120 is preferably so shaped and finished as to simulate the 20 top of a fire hydrant.

If desired, additional ornaments may be added to the toy. In the present case base 16 carries a simulated lamp post and fire alarm box 130, 25 and the mounting is preferably made detachable, as by the use of a foot 132 on the lamp post which is slidably received beneath a strap 134 displaced upwardly from the base. This assembly is convenient for packing and shipping 30 the toy.

It is believed that the mode of constructing and using, as well as the many advantages of my improved toy, will be apparent from the foregoing detailed description thereof. The climbing 35 fireman toy is improved in construction, and the realism and play value of the toy are enhanced by the simulated rescue of the infant and also by the hose equipment particularly in view of the actual discharge of water therefrom. It will be 40 understood that these additional features may be used singly as well as in combination. For example, the infant may be left away from the toy when the hose is used, and, conversely, the hose may be freed from its support and left at one 45 side while the apparent rescue is being effected. The hose and pump may be used separately.

It will be apparent that while I have shown and described my invention in preferred form, many changes and modifications may be made in 50 the structure disclosed without departing from the spirit of the invention, defined in the following claims.

I claim:

1. A climbing figure toy comprising a ladder, 55 a simulated fireman or other figure having a body, arms extending from said body toward said ladder and slidable therealong, legs movably mounted near the lower end of the body and having feet adapted to be moved between the rungs of the ladder, a motor in the body of said fireman connected to said legs, the resulting movement of the feet causing the fireman to climb upwardly on the ladder, and inwardly notched stops formed on the ladder near the upper end thereof to stop the fireman at the top of the ladder, said stops forming no obstruction to sliding of the fireman onto the ladder over the top end thereof.

2. A climbing figure toy comprising a ladder, 70 a simulated fireman or other figure slidable along said ladder, a spring motor in said fireman causing the fireman to move on the ladder, a figure toy provided with means for supporting the same on the ladder, and cooperating means on said 75

figure top and on said fireman, adapting said fireman to carry the figure toy during its movement on the ladder.

3. A climbing fireman toy comprising a ladder, a simulated fireman having a body, arms extending from said body toward said ladder and slideable therealong, legs movably mounted near the lower end of the body, feet adapted to be moved between the rungs of the ladder, a spring motor in the body of said fireman, and cranks rotated by said motor and connected to said legs, the resulting movement of the feet causing the fireman to climb upwardly on the ladder, a figure toy provided with means for supporting the same at an intermediate point on the ladder, and cooperating means on said figure toy and on said fireman, whereby said fireman carries the figure toy upwardly during his ascent on the ladder.

4. A climbing fireman toy comprising a ladder, a simulated fireman having a body, arms extending from said body toward said ladder and slideable therealong, legs pivotally and slideably mounted near the lower end of the body, leg extensions projecting upwardly within the body, feet adapted to be moved between the rungs of the ladder, a spring motor in the body of said fireman, and oppositely directed cranks rotated by said motor and connected to said legs extensions within said body, the resulting movement of the feet causing the fireman to climb upwardly on the ladder, a simulated infant provided with means for supporting the same at an intermediate point on the ladder, and cooperating means on said infant and on the arms of said fireman, whereby said fireman carries the infant upwardly during his ascent on the ladder.

5. A climbing fireman toy comprising a ladder, a simulated fireman slideable therealong, a spring motor in said fireman causing the fireman to move on the ladder, a flexible rubber water hose, a nozzle at the discharge end of said hose, and means on said fireman for receiving and holding the hose at the nozzle.

6. A climbing fireman toy comprising a ladder, a simulated fireman having a body, arms extending from said body toward said ladder and slideable therealong, legs movably mounted near the lower end of the body, feet adapted to be moved between the rungs of the ladder, a spring motor in the body of said fireman, and cranks rotated by said motor and connected to said legs, the resulting movement of the feet causing the fireman to climb upwardly on the ladder, a flexible rubber water hose, a nozzle at the discharge end of said hose, means on said fireman for detachably receiving and holding the hose at the nozzle, and a source of water supply connected to the opposite end of the hose.

7. A climbing fireman toy comprising a ladder, a simulated fireman having a body, arms extending from said body toward said ladder and slideable therealong, legs pivotally and slideably mounted near the lower end of the body, leg extensions projecting upwardly within the body, feet adapted to be moved between the rungs of the ladder, a spring motor in the body of said fireman, and oppositely directed cranks rotated by said motor and connected to said leg extensions within said body, the resulting movement of the feet causing the fireman to climb upwardly on the ladder, a flexible rubber water hose, a nozzle at the discharge end of said hose, a bent wire support on said fireman for detachably receiving and holding the hose near the nozzle in a direction away from the ladder, and a source of

water supply connected to the opposite end of the hose.

8. A toy comprising in combination, a flexible rubber water hose having a nozzle at the discharge end of said hose, and a source of water supply connected to the opposite end of the hose, said source comprising a water containing casing simulating a fire hydrant, a pump concealed therein, said pump having suitable intake and exhaust valves for positive pressure ejection of water, and means to operate said pump including a reciprocable button projecting from the casing and simulating a part of the fire hydrant.

9. A toy comprising in combination, a flexible rubber water hose having a nozzle at the discharge end of said hose, and a source of water supply connected to the opposite end of the hose, said source comprising a water containing casing simulating a fire hydrant, a flexible rubber ball, means supporting the same near the top of the casing, a valved intake pipe depending from said ball to the bottom of the casing, a valved discharge pipe extending sidewardly from said ball to the lower end of the hose, and a vertically reciprocable button projecting from the top of the casing immediately above said ball and simulating the top of the fire hydrant.

10. A climbing fireman toy comprising a ladder, a simulated fireman slideable therealong, a spring motor in said fireman causing the fireman to move on the ladder, a water hose, a nozzle at the discharge end of said hose, means on said fireman for receiving and holding the hose at the nozzle, and a source of water supply connected to the opposite end of the hose, said source comprising a water containing casing simulating a fire hydrant, and pump means for forcing the water through the hose.

11. A climbing fireman toy comprising a ladder, a simulated fireman having a body, arms extending from said body toward said ladder and slideable therealong, legs movably mounted near the lower end of the body, feet adapted to be moved between the rungs of the ladder, a spring motor in the body of said fireman, and cranks rotated by said motor and connected to said legs, the resulting movement of the feet causing the fireman to move on the ladder, a water hose, a nozzle at the discharge end of said hose, means on said fireman for receiving and holding the hose at the nozzle, and a source of water supply connected to the opposite end of the hose, said source comprising a water containing casing simulating a fire hydrant, pump means in said casing, and means to operate said pump including a reciprocable button projecting from the casing and simulating a part of the fire hydrant.

12. A climbing fireman toy comprising a ladder, a simulated fireman having a body, arms extending from said body toward said ladder and slideable therealong, legs pivotally and slideably mounted near the lower end of the body, leg extensions projecting upwardly within the body, feet adapted to be moved between the rungs of the ladder, a spring motor in the body of said fireman, and oppositely directed cranks rotated by said motor and connected to said leg extensions within said body, the resulting movement of the feet causing the fireman to climb upwardly on the ladder, a flexible rubber water hose, a nozzle at the discharge end of said hose, means on said fireman for detachably receiving and holding the hose at the nozzle, and a source of water supply connected to the opposite end of the hose, said source comprising a water con-

taining casing simulating a fire hydrant, a flexible rubber ball, means supporting the same near the top of the casing, a valved intake pipe depending from said ball to the bottom of the casing, a valved discharge pipe extending sidewardly from said ball to the lower end of the fire hose, and a vertically reciprocable button projecting from the top of the casing immediately above said ball and simulating the top of the fire hydrant.

13. In a climbing figure toy in which a simulated figure climbs a ladder, a knock-down ladder structure comprising a base, ears projecting upwardly at one part of said base, a ladder having its lower end pivotally mounted on said ears, a generally U-shaped wire support for holding said ladder in elevated position, the bottom part of the support being pivotally mounted on the base at a point remote from the aforesaid pivotal mounting of the ladder, the open ends of the support being bent to detachably fit mating parts of the ladder, whereby the support and the ladder may be disconnected and folded in collateral relation in the direction of the base when the top is not in use.

14. In a climbing figure toy in which a simulated figure climbs a ladder, a part of said figure sliding along the poles of the ladder, a sectional knock-down ladder structure, said ladder structure comprising a plurality of sections each including poles connected by transverse rungs, the adjacent ends of the poles being arranged to fit together, one of said poles being provided with a projecting part of reduced size dimensioned to be received in the end of the adjacent pole, whereby said poles fit together to form a smooth continuous pole of uniform size.

15. In a climbing figure toy in which a simulated figure climbs a ladder, a part of said figure sliding along the poles of the ladder, a knock-down ladder structure comprising a base, a sectional ladder, and a support, said ladder including a plurality of sections each having poles connected by transverse rungs, the adjacent ends of the poles being arranged to fit together, one pole

end being so reduced in dimension as to be received in the adjacent pole end whereby the poles fit together to form a smooth, continuous pole, the lowermost ladder section being pivoted at one part of the base, the support being pivoted at another part of the base, the opposite end of the support being arranged to be detachably received by a part of the first ladder section in order to hold the same in elevated position, the support and the bottom ladder section when disconnected being adapted to be folded in collateral relation parallel to the base.

16. In a climbing figure toy in which a simulated figure climbs a ladder, a part of said figure sliding along the poles of the ladder, a sectional knock-down ladder structure, said structure comprising a plurality of ladder sections, each section being made of a single piece of sheet metal stamped to form vertical strips connected by transverse rungs, said vertical strips being rolled to form smooth cylindrical poles between which extend the integrally formed rungs, the adjacent ends of the poles of the sections being mated together by means of a cylindrical projecting part of reduced diameter on one pole end dimensioned to be received in the adjacent pole end, whereby the sections fit together to form smooth continuous poles of uniform diameter.

17. A climbing figure toy comprising a ladder, a simulated figure having a body, arms extending from said body towards said ladder and slideable therealong, legs movably mounted near the lower end of the body and having feet adapted to be moved between the rungs of the ladder, a motor in the body of the figure connected to said legs, the resulting movement of the feet causing the figure to climb upwardly on the ladder, and means formed on and localized at one part of the ladder to stop the figure from continued upward climbing when the figure reaches said means, said means being so formed as to present no obstruction to sliding of the figure downwardly on the ladder over the said means.
